CLAIM

The ornamental design for an oval dentifrice patch, as shown and described.

DESCRIPTION

FIG. 1 is a perspective elevation view of an oval dentifrice patch;

FIG. 2 is a front plan view thereof;

FIG. 3 is a left side plan view thereof;

FIG. 4 is a rear plan view thereof;

FIG. 5 is a right side plan view thereof;

FIG. 6 is a top plan view thereof; and,

FIG. 7 is a bottom plan view thereof.

The broken line disclosure of the toothbrush illustrates the environment and forms no part of the claimed design. The unshaded area within the patch that is defined by broken lines illustrates a portion of the article and forms no part of the claimed design.
